UNITED STATES PATENT OFFICE

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-TRAFFIC-CONTROLLING APPARATUS

Application filed October 9, 1929. Serial No. 398,334.

My invention relates to railway traffic controlling apparatus, and particularly to apparatus of the type involving brake-applying and speed-governing means on a train controlled by suitable devices in the trackway.

One feature of my invention is the provision of novel and improved means for preventing an automatic brake application and imposing a fixed speed limit on a train in the event of acknowledgment by the engineer of a restrictive signal indication.

I will describe certain forms of apparatus embodying my invention, and will then point out the novel features thereof in claims.

In the accompanying drawings, Fig. 1 is a diagrammatic view showing one form of trackway apparatus embodying my invention. Fig. 2 is a view, partly diagrammatic and partly in section, showing one form of train carried apparatus embodying my invention, and suitable for use with the trackway apparatus shown in Fig. 1. Fig. 3 is a diagrammatic view showing a modification of the trackway apparatus illustrated in Fig. 1 and also embodying my invention. Fig. 4 is a view showing a modification of the train carried apparatus shown in Fig. 2 and suitable for use with the trackway apparatus shown in Fig. 3 and also embodying my invention.

Similar reference characters refer to similar parts in each of the several views.

Referring first to Fig. 1, the reference characters 1 and 1^a designate the track rails of a stretch of railway track along which traffic normally moves in the direction indicated by the arrow. These rails are divided by insulated joints 2 to form a plurality of track sections A—B, B—C, etc. Each section is provided with a track circuit comprising a transformer 3, the secondary of which is connected across the rails at the leaving end of the section, and a track relay R having a winding connected across the rails at the entrance end of the section. Each track section is provided with an additional insulated joint 8, located in rail 1^a, a short distance in the rear of the leaving end of the section, and this joint may conveniently be one or two rail lengths in the rear of the insulated

joint 2 in the same rail at the leaving end of the section. Connected around each joint 8 is the primary of a transformer 9, the secondary of which is connected with the input terminals of a full-wave rectifier 10. An auxiliary track relay X is connected with the output terminals of each rectifier. Each auxiliary relay X will, therefore, be energized at all times except when the wheels and axles of a train are between the associated insulated joint 8 and the point at which transformer 3 is connected with the track rails. Each track section is provided with a train stopping device designated by the reference character T with a suitable exponent. As here shown, each of these devices is of the mechanical trip type, comprising an arm which normally occupies an active or tripping position, but which may be moved to an inactive or non-tripping position by the energization of a mechanism which forms a part of the device. Each device is located in the rear of the associated section, and is preferably located very close to the insulated joint 8 in the section next in the rear. Each of these devices T is provided with a main circuit and an auxiliary circuit. Considering the device T^B, for example, the main circuit for this device is from terminal B of a suitable source of current, through front contact 4 of track relay R^C, front contact 6 of auxiliary relay X^C, front contact 5 of track relay R^B, and the operating mechanism of the device T^B, to the other terminal of the same source of current. It follows that so far as this circuit is concerned, the device T^B will be held in its non-tripping position when sections B—C and C—D are unoccupied, but will assume its tripping position when either or both of these sections are occupied by a car or train. The auxiliary circuit for device T^B is from terminal B, through back contact 7 of relay X^B, and the operating mechanism of the device T^B to terminal O. It follows that, regardless of the condition of the main circuit, the device T^B will occupy its non-tripping position whenever an axle and pair of wheels occupy that portion of section A—B which lies between the insulated

joint 8 and the point of connection of the transformer 3 with the track rails.

Referring now to Fig. 2, it is to be understood that all of the apparatus shown in this view is carried on a car or other railway vehicle, and that this car is provided with a pipe U which, when vented to atmosphere, will cause an automatic application of the brakes. For present purposes, I will assume that this pipe is the brake pipe of the usual braking system. Connected with the brake pipe U is a brake application valve F, comprising a valve member 21 which is biased by a spring 22 to such position as to close an exhaust port 55 leading to atmosphere. The pressure on the two sides of the valve member 21 is equalized by a small orifice 21^a in this member, whereby when the pipe 23 connected with the right-hand end of the valve is closed, the pressure is equalized and the valve member 21 occupies its left-hand position wherein the exhaust port 55 is closed. When pipe 23 is opened to atmosphere, however, the pressure on the right-hand side of member 21 is reduced, whereupon the brake pipe pressure on the left-hand side of this member will cause the member to be moved to the right to open the brake pipe U to atmosphere through the port 55. Member 21 will then remain in its right-hand position until the pressure in the brake pipe is reduced to a very small value, whereupon this member will be restored to its closing position by the action of spring 22.

The brake application valve F is at times controlled by a pilot valve G, which in turn is controlled by the trackway tripping devices T of Fig. 1. This pilot valve G comprises a trip arm 11 which projects downwardly and is arranged to be engaged by each trackway device T when such device is in the tripping position but not when the device is in the non-tripping position. The trip arm 11 is biased by centering springs (not shown) to a middle position so that it automatically returns to this position after it has been swung by a tripping device T. When the trip arm 11 is swung by the tripping device, a cam 13 attached to this arm will raise a roller 14 attached to a vertically sliding member 56, and this member in turn will raise a valve 16 which is attached to a sliding piston 12. A pipe 15 enters the lower end of the casing of the valve G, and this pipe is disconnected from atmosphere when the valve 16 is closed. When the valve 16 is raised by the operation of trip arm 11, a passage 17 will be connected to atmosphere through an exhaust port 57, reducing the pressure above piston 12 so that the pressure in pipe 15 acting on the underside of this piston will cause the piston to rise further against the action of a spring 19, thus providing a direct connection from pipe 15 through valve 16 and port 57 to atmosphere. As the pressure in pipe 15 is reduced, spring 19 will tend to close valve 16, but this valve

is so constructed that the exhaust from pipe 15 is cut off before piston 12 reaches its lowest position. It follows that the outflowing air will maintain a differential pressure on piston 12 to hold valve 16 open. In order to close valve 16 the motorman must reduce the pressure in pipe 15 to a very low pressure so that the pressure below piston 12 will be less than the pressure exerted by spring 19. A valve device of this character is disclosed in Patent No. 1,243,782 granted to W. V. Turner on October 23, 1917.

The pipe 15 is normally connected with pipe 23 through a pipe 41 and a port 42 in a forestalling valve K hereinafter explained, with the result that if the trip arm 11 is operated by a trackway device T, the pressure in pipes 15 and 23 will be reduced so that the brake application valve F will be opened to cause an automatic application of the brakes unless the engineer takes proper action as herein-after explained.

Also connected with the pipe 23 is an auxiliary pilot valve H comprising a valve member 24 biased by a spring 25 to an open position but normally held closed against the action of this spring by fluid pressure acting on a diaphragm 27. When the pressure on diaphragm 27 is reduced, the valve member 24 will move to the right, thereby connecting the pipe 23 with atmosphere through an exhaust port 26, with the result that the brake application valve F will be operated to cause an automatic application of the brakes.

The forestalling valve K comprises a valve body 30 containing a slide valve 31 operated by a piston 32 sliding in a cylinder formed in the left-hand end of the valve body 30. The valve body 30 is constantly connected with a source of fluid pressure, such as the main reservoir of the braking system, through a pipe 58^a, and the piston 32 is provided with a small orifice 32^a, so that normally the pressures on the two sides of this piston are equalized. The slide valve is biased toward the right by a spring 33, so that when the air pressures on the two sides of piston 32 are equalized, this piston and the slide valve occupy their right-hand positions, in which they are shown in the drawing.

The pressure on the left-hand side of piston 32 may be reduced by the operation of a manual forestalling device L. This device comprises a normally closed push button valve connected with a pipe 34, which pipe in turn is connected with the cylinder on the left-hand side of piston 32. It follows that normally the pipe 34 is closed, but that when the push button valve L is operated, this pipe will be opened to atmosphere through an exhaust port 35, so that the pressure on the left-hand side of piston 32 will be reduced. This will result in a movement of the piston and slide valve to the left, whereupon, the left-hand side of piston 32 will become connected

with a timing reservoir 38 through a passage 36 in the body of the forestalling valve, a port 39 in the slide valve 31, and a pipe 37. The pipe 37 is normally connected with atmosphere through the port 39 and an exhaust port 40. When the slide valve is moved to the left, the chamber at the left of the piston is connected through port 31 to the empty reservoir 38 which will then charge slowly through piston orifice 32^a so that a considerable period of time will elapse before the pressure on the left-hand side of the piston reaches substantially the same value as the pressure on the right-hand side. This period of time may, for example, be 30 seconds. When the pressures have become substantially equalized, the piston 32 and slide valve 31 will be returned to their right-hand positions due to the pressure exerted by spring 33.

When the forestalling valve K is in its normal position, the diaphragm 27 of the auxiliary pilot valve H is connected, through port 43 in slide valve 31 and pipe 28, with pipe 23 58^a which leads to a source of fluid pressure, so that valve member 24 is held closed and the valve H can have no influence on the brake application valve F.

When the forestalling valve K is reversed, pipe 41 will be disconnected from pipe 15 and the former pipe will be blanked by the slide valve 31, so that the pilot valve G will be disconnected from the brake application valve F. At the same time, pipe 28 will be disconnected from the source of fluid pressure and will be connected by port 44 with a pipe 29 leading to a speed control valve N. The valve N comprises a valve member 49 controlled by a speed control magnet M in such manner that when the magnet is energized the pipe 29 is connected with a pipe 58^b leading to the source of fluid pressure; whereas, when the magnet is de-energized the pipe 29 is disconnected from pipe 58^b and is connected with atmosphere through an exhaust port 50 and also with a whistle W.

The magnet M is provided with a circuit which includes a contact 53 operated by a speed governor P, which in turn is operationally connected with a car axle 52. Contact 53 is closed or open according as the speed of the car is below or above a given value, such as ten miles per hour. The circuit for magnet M also includes a normally open cut-out contact 48 operated by a pressure-responsive device Q. This device may, for example, be of the Bourdon tube type. When the forestalling valve K is in its normal position, the pressure-responsive device Q is connected with atmosphere through a pipe 46, a port 45 in the slide valve 31 and an exhaust port 47; under this condition, the contact 48 is open. When the forestalling valve is reversed, however, pipe 46 is disconnected from atmosphere and is opened to the body

of the valve K, and so is supplied with fluid pressure through pipe 58^a. Under this condition the cut-out contact 48 is closed.

Referring now to Figs. 1 and 2, the operation of the system as a whole is as follows:

As shown in Fig. 1, section C—D is occupied by a train E, so that tripping devices T^c and T^b are both in their tripping positions, and signals S^c and S^b both indicate "Stop". Tripping device T^a at the entrance to section A—B is in its non-tripping position, and the signal S^a for this section indicates "Caution".

I will now assume that a car or train equipped with the apparatus shown in Fig. 2 enters the stretch of track shown in Fig. 1. As this train approaches section A—B, it will not be affected by the tripping device T^a, but as the train approaches section B—C, the pilot valve G will be operated by the tripping device T^b and the brakes will be automatically applied unless the engineer operates the forestalling push button L. If the engineer does operate this button, the pressure on the left-hand side of piston 32 of the forestalling valve K will be reduced, so that this valve will be reversed, with the result that the pilot valve G will be disconnected from the brake valve F, and the operation of the pilot valve G by the tripping device will not cause an automatic application of the brakes. At the same time, the auxiliary pilot valve H will be connected with the speed control valve M. The cut-out contact 48 will be closed, so that if the speed of the train is below 10 miles per hour magnet M will be energized, with the result that the auxiliary pilot valve H will be supplied with fluid pressure from pipe 58^b and so this valve will be held closed. If, however, the speed of the train is above ten miles per hour, magnet M will be de-energized, so that pipe 29 will be connected with atmosphere, with the result that pilot valve H will open and so will reduce the pressure in pipe 23 to cause an automatic application of the brakes. The forestalling valve K will remain in its reversed position for 30 seconds, and if at any time during this period the speed of the train exceeds 10 miles per hour, magnet M will become de-energized and an automatic application of the brakes will occur. For ordinary lengths of track sections, the period of 30 seconds will be sufficient to insure that the train will be unable to accelerate to a dangerous speed before reaching the next signal.

When the train passes the tripping device T^b, it will open the auxiliary relay X^b, thereby closing the auxiliary circuit for the tripping device T^b, with the result that this device will be held in its non-tripping position as long as any part of the train is passing over it. It follows that if the train is equipped with any other pilot valves G, such other valves will not be operated by this de-

vice. When the train passes the tripping device T^c , the engineer must again acknowledge by the operation of the push button L in order to avoid an automatic brake application.

5 The reason for the insulated joints 8 and the auxiliary track relays X , is to insure that if two trains are separated by one or more train lengths, the second train will always have automatic stop protection. In 10 other words, the apparatus provides for recurrent acknowledgement at each successive stop signal passed by a train which is following closely a train ahead moving at slow speed.

15 Returning to the operation of the apparatus shown in Fig. 2, I will assume that the engineer has acknowledged a stop signal, and that during the 30-second time interval provided by the timing reservoir 38 the speed of 20 the train rises above 10 miles per hour. This will result in the opening of contact 53 , so that magnet M will become de-energized. A timing reservoir 59 is connected with the pipe 28 and is so proportioned as to provide a time interval of about 5 seconds between the 25 reversal of valve 49 and the reversal of the diaphragm 27 . During this 5-second interval, the exhaust of air from pipe 29 will cause the whistle W to sound, thereby notifying the engineer that unless the speed of the train is immediately reduced to 10 miles per hour a brake application will occur. If the speed is reduced to this value prior to the 30 operation of valve H , the automatic application of the brakes will be prevented. When the 35 30-second interval provided by the timing reservoir 38 expires, the forestalling valve K will return to its normal position, and the engineer will be apprised of this fact 40 by a short blast from the whistle W due to the escape of pressure in pipe 29 when magnet M is de-energized.

45 Referring now to Figs. 3 and 4, the apparatus shown in these views is the same as that shown in Figs. 1 and 2, except as to the means for restoring the acknowledging valve K to its normal position after it has been reversed by the operation of the push button L . In Fig. 4 the pipe 37 , instead of leading to a timing reservoir, leads to a reset valve N^R comprising a valve member 70 controlled by a reset magnet M^R . When the magnet is de-energized, pipe 37 is connected with atmosphere through an exhaust port 71 , so that after the forestalling valve K has 50 been reversed it will stay in the reverse position until magnet M^R becomes energized. When this occurs, valve 70 will be reversed to disconnect pipe 37 from atmosphere and to 55 connect this pipe with a pipe 58^c leading to the source of fluid pressure.

60 The reset magnet M^R is controlled by a reset relay J , which in turn is controlled by a train carried receiver Z co-acting with track-way inductors Y . Referring to Fig. 3, an in-

70 ductor Y is located adjacent each signal. The winding 61 of each inductor Y is provided with a circuit which passes from terminal V of a source of alternating current, through front contact 60 of the adjacent track relay R , and the winding 61 to terminal O of the same source. It follows that each inductor Y is energized when the associated track relay is energized, and de-energized when the track relay is de-energized. Although as illustrated in the drawing each inductor Y is located a short distance in advance of the entrance to the associated section, this is done only to avoid crowding the drawing; in actual practice each inductor is located substantially opposite the insulated joints so that it will not become de-energized until after it has been passed by the receiver Z .

75 Referring again to Fig. 4, the receiver Z is provided with a winding 72 which is connected with the input terminals of a full-wave rectifier 62 , a condenser 63 being connected across the terminals of the winding 72 for tuning and filtering purposes. The 80 output terminals of the rectifier 62 are connected with the winding of the reset relay J . It follows that when the train passes over an energized trackway inductor, relay J will be momentarily energized and so will close its front contacts. If the forestalling valve has been reversed, and if the speed of the train is below 10 miles per hour, a stick circuit for relay J will then be closed, which 85 circuit passes from terminal B , through speed governor contact 53 , wire 64 , contact 48^a of the pressure-responsive device Q , wires 65 and 66 , front contact 67 of relay J , and the winding of this relay to terminal O . Relay J will therefore remain energized until either contact 53 or contact 48^a opens. Magnet M^R will then become energized by a circuit which passes from terminal B , through speed governor contact 53 , wire 64 , cut-out 90 contact 48^a , wires 65 and 66 , contact 73 of relay J , wires 68 and 69 , and the winding of magnet M^R to terminal O . This will cause magnet M^R to become energized, and this in turn will reverse valve member 70 of the 95 reset valve N^R , so that pipe 37 will be connected with the source of fluid pressure, with the result that the forestalling valve K will return to its normal position. This will cut off the source of fluid pressure from the 100 pressure-responsive device Q , so that contact 48^a will open, with the result that the reset magnet M^R and the reset relay J will both become 105 de-energized.

110 It follows from the foregoing that with the apparatus shown in Figs. 3 and 4, when the engineer has acknowledged a stop signal, the speed limit imposed by contact 53 will remain effective until the train reaches the next signal giving a caution or proceed indication,

that is, until the train enters a track section the track relay R of which is energized.

In Fig. 2, the wire 54 may extend to corresponding equipment at the other end of the car or train, it being noted that one centrifugal device P is all that is necessary for each car or group of cars provided with the apparatus shown in this view. The same thing is true in Fig. 4, except that the three wires 64, 65 and 69 would then be extended to the equipment at the other end of the car or train, only one reset relay, rectifier, receiver, and centrifugal device being required, regardless of the number of train control equipments on the car or train.

Although I have herein shown and described only a few forms of apparatus embodying my invention, it is understood that various changes and modifications may be made therein within the scope of the appended claims without departing from the spirit and scope of my invention.

Having thus described my invention, what I claim is:

1. Train carried brake controlling apparatus comprising a brake application valve, a pilot valve controlled from the trackway and normally connected with said brake application valve, an auxiliary pilot valve constantly connected with said brake application valve, but normally held closed regardless of the speed of the train, and manually operable means for disconnecting said trackway controlled pilot valve from said brake valve and placing said auxiliary pilot valve under the control of the train speed.

2. Train carried brake controlling apparatus comprising a brake application valve, a pilot valve controlled from the trackway and normally connected with said brake application valve, an auxiliary pilot valve constantly connected with said brake application valve, but normally held closed regardless of the speed of the train, a speed governor operatively connected with an axle of the train, a contact operated by said governor and closed or open according as the train speed is below or above a given value, a normally open cut-out contact, a speed control magnet, a circuit for said magnet including said speed governor contact and said cut-out contact, a speed control valve operated by said magnet, and manually operable means for disconnecting said trackway controlled pilot valve from said brake valve and at the same time closing said cut-out contact and placing said auxiliary pilot valve under the control of said speed control valve.

3. Train carried brake controlling apparatus comprising a brake application valve, a pilot valve controlled from the trackway and normally connected with said brake valve, an auxiliary pilot valve constantly connected with said brake valve, a pneumatic device for operating said auxiliary pilot valve and nor-

mally connected with a source of fluid pressure to hold the valve closed, a pipe, manually operable means for disconnecting said trackway controlled valve from said brake valve and for at the same time disconnecting said pneumatic device from said source of fluid pressure and connecting it with said pipe, and means for connecting said pipe with said source of fluid pressure or with atmosphere according as the speed of the train is below or above a given value.

4. Train carried brake controlling apparatus comprising a brake application valve, a pilot valve controlled from the trackway and normally connected with said brake valve, an auxiliary pilot valve constantly connected with said brake valve, a pneumatic device for operating said auxiliary pilot valve and normally connected with a source of fluid pressure to hold the valve closed, a pipe, a speed control magnet, a speed control valve operated by said magnet for connecting said pipe with a source of fluid pressure or with atmosphere according as the magnet is energized or de-energized, a normally open cut-out contact, a speed controlled contact closed or open according as the speed of the train is below or above a given value, a circuit for said magnet including said cut-out contact and said speed controlled contact, and manually operable means for disconnecting said trackway controlled pilot valve from said brake valve and at the same time disconnecting said pneumatic device from the source of pressure and connecting it with said pipe and also closing said cut-out contact.

5. Train carried brake controlling apparatus comprising a brake application valve, a pilot valve controlled from the trackway and normally connected with said brake application valve, an auxiliary pilot valve constantly connected with said brake application valve, but normally held closed regardless of the speed of the train, a forestalling valve having a normal position, manually operable means for reversing said forestalling valve, and means responsive to reversal of said forestalling valve for disconnecting said trackway controlled pilot valve from said brake valve and placing said auxiliary pilot valve under the control of the speed of the train.

6. Train carried brake controlling apparatus comprising a brake application valve, a pilot valve controlled from the trackway and normally connected with said brake application valve, an auxiliary pilot valve constantly connected with said brake application valve, but normally held closed regardless of the speed of the train, a speed governor operatively connected with an axle of the train, a contact operated by said governor and closed or open according as the train speed is below or above a given value, a normally open cut-out contact, a speed control magnet, a cir-

cuit for said magnet including said speed governor contact and said cut-out contact, a speed control valve operated by said magnet, a forestalling valve having a normal position, 5 manually operable means for reversing said forestalling valve, and means operating when said forestalling valve is reversed to disconnect said trackway controlled pilot valve from said brake valve and to close said cut-out contact and to also place said auxiliary valve under the control of said speed control valve.

7. Train carried brake controlling apparatus comprising a brake application valve, a 15 pilot valve controlled from the trackway and normally connected with said brake application valve, an auxiliary pilot valve constantly connected with said brake application valve, but normally held closed regardless of 20 the speed of the train, a forestalling valve having a normal position, manually operable means for reversing said forestalling valve, means controlled from the trackway for restoring said forestalling valve to its normal 25 position, and means operating while said forestalling valve is in the reversed position to disconnect said trackway controlled pilot valve from said brake valve and to place said auxiliary pilot valve under the control of the 30 speed of the train.

8. Train carried brake controlling apparatus comprising a brake application valve, a pilot valve controlled from the trackway and normally connected with said brake application valve, an auxiliary pilot valve constantly connected with said brake application valve, but normally held closed regardless of the speed of the train, a speed governor operatively connected with an axle of the train, a contact operated by said governor and closed or open according as the train speed is below or above a given value, a normally open cut-out contact, a speed control magnet, a circuit for said magnet including said speed governor 45 contact and said cut-out contact, a speed control valve operated by said magnet, a forestalling valve having a normal position, manually operable means for reversing said forestalling valve, a reset valve arranged when energized to restore said forestalling valve to its normal position, a reset magnet for the control of said reset valve, a reset relay, means controlled from the trackway for momentarily energizing said reset relay, a stick circuit for said reset relay including said speed governor contact and said cut-out contact, a circuit for said reset magnet including a front contact of said reset relay and said cut-out 50 contact as well as said speed governor contact, and means operating while said forestalling valve is in its reversed position to disconnect said trackway controlled pilot valve from said brake valve and to close said 55 cut-out contact as well as to place said auxil-

iary pilot valve under the control of said speed control valve.

9. Train carried brake controlling apparatus comprising a brake application valve, a pilot valve controlled from the trackway, 70 an auxiliary pilot valve connected with said brake application valve, a forestalling device having a normal position, manual means for reversing said device, means operating when said device is in the normal position for 75 connecting said trackway controlled pilot valve with said brake valve and rendering said auxiliary pilot valve ineffective regardless of the speed of the train, and means operating when said forestalling device is reversed to disconnect said trackway controlled pilot valve from said brake valve and to place said auxiliary pilot valve under the control of the train speed.

10. Train carried brake controlling apparatus comprising a brake application valve, a pilot valve controlled from the trackway and normally connected with said brake application valve, an auxiliary pilot valve constantly connected with said brake application valve, but normally held closed regardless of the speed of the train, a forestalling valve having a normal position, a manually operable forestalling member, means responsive to momentary operation of said forestalling member for reversing said forestalling valve and holding it in the reversed position for a given interval of time, and means operating while said forestalling valve is in the reversed position to disconnect said trackway controlled pilot valve from said brake valve and to place said auxiliary pilot valve under the control of the speed of the train.

In testimony whereof I affix my signature.

LLOYD V. LEWIS.
